(57) **CLAIM**

The ornamental design for a battery case with cover, as shown and described.

DESCRIPTION

FIG. 1 is an isometric view of a first embodiment of a battery case with cover showing our new design;

FIG. 2 is a front view of the battery case with cover shown in FIG. 1;

FIG. 3 is a rear view of the battery case with cover shown in FIG. 1;

FIG. 4 is a right side view of the battery case with cover shown in FIG. 1;

FIG. 5 is a left side view of the battery case with cover shown in FIG. 1, taken from the side opposite FIG. 4;

FIG. 6 is a top view of the battery case with cover shown in FIG. 1;

FIG. 7 is a bottom view of the battery case with cover shown in FIG. 1;

FIG. 8 is isometric view of a second embodiment of a battery case with cover

FIG. 9 is a front view of the battery case with cover shown in FIG. 8;

FIG. 10 is a rear view of the battery case with cover shown in FIG. 8;

FIG. 11 is a right side view of the battery case with cover shown in FIG. 8;

FIG. 12 is a left side view of the battery case with cover shown in FIG. 8, taken from the side opposite FIG. 11;

FIG. 13 is a top view of the battery case with cover shown in FIG. 8; and,

FIG. 14 is a bottom view of the battery case with cover shown in FIG. 8.

The broken lines are shown for the purpose of illustrating parts of the article that form no part of the claim. Further, the portions of the battery case and/or cover that are not shown in the drawings do not form any part of the claimed design.
